UNITED STATES PATENT OFFICE

145,176

DESIGN FOR A BUTTON OR SIMILAR ARTICLE

Maurice N. Lidz, Woodmere, N. Y.

Application April 1, 1946, Serial No. 128,131

Term of patent 7 years

(Cl. D17—2)

To all whom it may concern:

Be it known that I, Maurice N. Lidz, a citizen of the United States, residing at Woodmere, in the county of Nassau and State of New York, have invented a new, original, and ornamental Design for a Button or Similar Article, of which the following is a specification, reference being had to the accompanying drawing, forming a part thereof.

Fig. 1 is a plan view of a button or similar article, showing my new design.

Fig. 2 is a top view thereof.

Fig. 3 is a side view thereof.

I claim:

The ornamental design for a button or similar article, substantially as shown.

MAURICE N. LIDZ.
